UNITED STATES PATENT OFFICE.

RICHARD MONTGOMERY, OF NEW YORK, N. Y.

IMPROVEMENT IN CORRUGATING METALLIC SHEETS.

Specification forming part of Letters Patent No. 24,480, dated June 21, 1859.

To all whom it may concern:

Be it known that I, RICHARD MONTGOMERY, of the city, county, and State of New York, have invented an Improvement in the Corrugated Metallic Plates or Sheets for Boilers, &c., patented to me on the 17th day of May, 1853; and I do hereby declare that the following is a full, clear, and exact description of the same, reference being had to the accompanying drawings, and to the letters of reference marked thereon, so as to enable others skilled in the art to make and use my invention.

Figure 1 represents a plan view of a corrugated plate with my improvement added thereto. Fig. 2 represents a cross-section through the plate shown in Fig. 1, the section being taken on line *a b*, Fig. 1. Fig. 3 represents part of a flue made from plates manufactured on the principle of my invention.

From Fig. 2 it will be seen that the flanges are made thicker than the corrugated portion of the plate, as provided for in my aforesaid patent, so as to afford suitable strength and form of metal for uniting the sheets.

My improvement will be readily understood from Figs. 1 and 2, where it will be seen the corrugations A B are not straight, as in my former patent, but are waved so that each of the ribs A B of the corrugated plates has a double curvature, one in the direction of its length, as seen in Fig. 1, and one across its width, as seen in Fig. 2. It will also be seen that each of these waved ribs or corrugations is longer than what a straight rib or corrugation would be. Consequently the surface of a plate provided with waved corrugations is greater than the surface of a plate with straight corrugations, while at the same time the corrugations are continuous from side to side, so that when bent together the ends of the corrugations will meet or be opposite to each other. Thus my waved and corrugated plates for boilers

offer a larger heating-surface than any other plate of the same dimensions provided with straight corrugations. Again, these plates provided with doubly-curved continuous ribs are far less liable to stretch in a direction across the ribs than plates which have straight continuous corrugations. When the waved corrugations are so arranged as to run in the direction of the flame, the heated gases striking one wave of the corrugations (the corrugations being continuous) will be deflected and impinge against the wave of the next corrugation, &c., as indicated by the arrow in Fig. 1, and thus the heated gases will be caused to act more effectually upon the surface of the plate. These plates possess another advantage which becomes apparent in the process of rolling the plates.

When plates with straight corrugations are rolled in such a manner that the corrugations run the same way as the fibers of the iron, then the fibers are liable to separate more or less, thereby vitiating the quality of the article. This difficulty is entirely obviated by waving the corrugations so that each corrugation along its whole length runs back and forth over various layers of fibers whichever way the plate may be rolled. It will be understood that the metal may be so rolled as to be thicker at the extreme points of the lateral waves than along the slopes or sides of the waves.

Having described my invention, what I claim, and desire to secure by Letters Patent as an improvement on the invention patented to me on the 17th day of May, 1853, is—

The waved corrugated wrought-metal plate for boilers, as herein described, in combination with flat margins of greater thickness than its middle, substantially as described.

R. MONTGOMERY.
